DESIGN FOR A TOURIST CAMP OFFICE BUILDING

Charles J. Greene, Dallas, Tex.

Application October 24, 1932. Serial No. 45,526

Term of patent 7 years

To all whom it may concern:

Be it known that I, CHARLES J. GREENE, a citizen of the United States, residing at 5033 Live Oak Street, in the city of Dallas, county of Dallas, and State of Texas, have invented a new, original, and ornamental Design for a Tourist Camp Office Building, of which the following is a specification, reference being had to the accompanying drawing, forming a part thereof.

Fig. 1 is a front elevation of a tourist camp office building constructed in accordance with the invention,

Fig. 2 is a side elevation of the same,
Fig. 3 is a rear view of the same, and

Fig. 4 is a side elevation opposite to that of Fig. 2.

The dominant features of the invention are the white sidings of the building and the comparatively prominent roof of ultra-marine blue color, the steep pitch roof with high end gables and a rearwardly extending sweeping shed roof.

The drawing is shaded for color.

I claim:

The ornamental design for a tourist camp office building as shown and described.

CHARLES J. GREENE.
